UNITED STATES PATENT OFFICE

WALTER B. SCOTT, OF MARBLEHEAD, MASSACHUSETTS

DESIGN FOR A TOY GOLF PLAYER

Application filed July 21, 1930. Serial No. 36,426. Term of patent 7 years.

To all whom it may concern:

Be it known that I, WALTER B. SCOTT, a citizen of the United States, residing at Marblehead, in the county of Essex and State of Massachusetts, have invented a new, original, and ornamental Design for a Toy Golf Player, of which the following is a specification, reference being made to the accompanying drawing, forming a part thereof.

The figure is a front perspective view of a toy golf player showing my new design.

I claim:

The ornamental design for a toy golf player as shown.

WALTER B. SCOTT.
